UNITED STATES PATENT OFFICE.

YASUKE KAWASAKI, OF VANCOUVER, BRITISH COLUMBIA, CANADA.

WAFER-LIFTING DEVICE.

No. 848,748.

Specification of Letters Patent.

Patented April 2, 1907.

Application filed November 30, 1906. Serial No. 345,780.

To all whom it may concern:

Be it known that I, YASUKE KAWASAKI, a citizen of the Japanese Empire, residing at the city of Vancouver, in the Province of 5 British Columbia, Canada, have invented a new and useful Improvement in Wafer-Lifting Devices, of which the following is a specification.

This invention relates to a device for detaching and removing from the plate on which they are baked thin flat wafer-biscuits of that kind known by the Japanese as "senbe." These biscuits, a number of which are formed and baked at one time by 5 pouring a fluid batter between two heated plates in a device which is the subject of a pending patent application, adhere strongly to the lower plate, owing to the presence of a considerable amount of sugar in the composition of the batter and to the fact that the batter is poured upon the lower plate while hot. As the wafers require to be removed from the plate as soon as baked and while in that condition are readily bent, while when 5 cool they become very brittle, it is necessary that whatever means is used to lift them from the plate should be such as will deliver them flat. Otherwise they will become broken in the packing. The most effective means which I have been able to devise to effect this lifting and removal comprises a series of thin flat resilient blades, the lower sharpened edges of which may be passed under the wafer and the form of which is such 5 that the wafer will lie flat on the surface of the blade and recover while hot the flatness which may have been somewhat disturbed in the act of lifting. This series of plates corresponds in number to the number of wafers to be lifted and is secured to a common frame by which they may be manipulated.

The construction and manner of using the device is fully described in the following specification, reference being made to the 5 drawings by which it is accompanied, Figure 1 being a vertical section through the device on the line A A in Fig. 3; Fig. 2, a vertical section on the line B B in Fig. 3, and Fig. 3 a plan of the device with a portion of the frame broken away to reveal the front of the lifting-blades.

In the drawings the upper surface of the baking-plate is represented by 2, and 3 indicates the wafers which the appliance is designed to lift from the plate and transfer to some other place to cool.

The lifting-blades are formed of thin resilient metal and have a flattened portion 4 inclined at an acute angle to the plane of the baking-plate and a sharpened lower edge 6 where it contacts with that plate. Above the flat portion 4 it is upwardly and forwardly bent, as at 5, to afford a sufficient amount of resilience and is thereafter bent backward, as at 6, to a plane parallel with the 65 baking-plate 2 and is by this portion 6 attached to the under side of a plate or preferably to the bars 10 of an open frame 11. By the use of an open frame the edges of the several blades can be viewed by the operator 70 during their application to the wafers.

The frame 11 is furnished with wooden handles 7, by which it is manipulated by the operator.

The several lifting-blades may either be 75 separately connected to the plate or frame by strips 8 and small bolts or screws 9, or each row of blades may be formed from one strip of thin metal and cut to form denticulations in the manner shown in the drawings. 80 It is necessary that each blade should be separated from the adjacent ones in the same row; otherwise the expansion of the lower edge where it contacts with the hot plate would distort that edge in a manner that 85 would prevent it being inserted under the wafers.

In the application of the device to lift and remove a series of wafers from a baking-plate the device is seized by the handles 7 and the 90 lower sharpened edges of the blades are inserted under the edges of the wafers. The device is then pushed forward with a quick movement, which transfers the wafers from the plate 2, and they are pushed up the incline of the blade and rest, as shown in Fig. 1, upon the flat portion 4 thereof, on the surface of which, if they have been slightly bent in the act of lifting, they will flatten of their own weight while still warm.

Having now particularly described my invention and the manner of its use, I hereby declare that what I claim as new, and desire to be protected in by Letters Patent, is—

1. As a wafer-lifting device a series of independently - resilient thin blades downwardly projecting at an acute incline from a common frame to which they are secured. 105

2. As a wafer-lifting device a series of independently - resilient inclined blades and 110 means for securing them to a common frame or plate.

3. As a wafer-lifting device an open frame having handles on the sides and a series of independently-resilient thin blades secured to the under side of the frame said blades being 5 first backwardly bent and then forwardly bent to form a flat surface at an acute angle to a common plane through the front lower edges of the blades.

In testimony whereof I have signed my name to this specification in the presence of two subscribing witnesses.

YASUKE KAWASAKI.
